PUSH-PULL SCREEN DOOR LATCH

Evelyn H. Greenwood, Buena Park, Calif., assignor to
Kwikset Locks, Inc., Anaheim, Calif., a corporation of
California

Application January 23, 1956, Serial No. 39,886

Term of patent 14 years

(Cl. D10—8)

Fig. 1 is a perspective view of a push-pull screen door latch, showing my new design;

Fig. 2 is a perspective view of the side opposite that shown in Fig. 1;

Fig. 3 is a top plan view;

Fig. 4 is a view taken in the direction of the arrow 4 of Fig. 1; and

Fig. 5 is a view taken in the direction of the arrow 5 of Fig. 1.

The broken line structure indicating a fragment of a door is for illustrative purposes only.

I claim:

The ornamental design for a push-pull screen door latch, as shown and described.
